United States Patent Office

Des. 183,836
Patented Nov. 4, 1958

183,836

COMBINED BEVERAGE AND FOOD VENDING BUILDING

Thurman W. Ganus, New Orleans, La.

Application July 15, 1957, Serial No. 46,953

Term of patent 14 years

(Cl. D13—1)

Figure 1 is a front perspective view of a combined beverage and food vending building showing my new design; and

Fig. 2 is a top plan view thereof.

The lining on the drawing represents contrasting color areas. The two sides not shown in Figure 1 have plain walls except for conventional windows and doors.

I claim:

The ornamental design for a combined beverage and food vending building, substantially as shown and described.
